FIG. 1 is a top perspective view of a pitcher or similar article showing my new design in the embodiment of a tea pot wherein the lid is a domed polygon.

FIGURE 2 is a side elevation of the same.

FIG. 3 is a top perspective view showing my new design in the embodiment of a water jug wherein the lid is a planar polygon with concentric base for the knob.

FIGURE 4 is a side elevation of the same.

FIG. 5 is a top perspective view of my new design in the embodiment of a coffee pot wherein the lid is a domed polygon.

FIGURE 6 is a side elevation of the same.

The design is characterized by a single handle, oppo-

sitely disposed spout, hinged polygonal lid and a body portion having fluted sidewalls each of which comprises the succession of polygons arranged as shown.

I claim:

The ornamental design for a pitcher or similar article, as shown and described.
